UNITED STATES PATENT OFFICE

ROY L. BARR, OF DETROIT, MICHIGAN, ASSIGNOR OF ONE-THIRD TO WALTER F. DUCKWITZ AND ONE-THIRD TO HOWARD VAN BRIGGLE, BOTH OF DETROIT, MICHIGAN

BURIAL VAULT

Application filed February 21, 1930. Serial No. 430,261.

The present invention relates to burial vaults and more especially to a combined casket and vault.

Among the objects of the invention is a combined casket and vault which may be easily and effectively sealed after receiving the body and again hermetically sealed as a vault and by means effectively preventing opening thereof.

10 Another object is a device of the character described which when being used as a casket permits ready concealment of the sealing means and presents the appearance of an ornamental casket.

15 Other objects will readily occur to those skilled in the art upon reference to the following description and the accompanying drawings in which

Fig. 1 is a perspective view of the device 20 with the vault cover removed and with one part of the glass cover elevated.

Fig. 2 is an enlarged sectional view of the vault cover locking means.

25 Fig. 3 is a section on line 3—3 of Fig. 2. Fig. 4 is a vertical cross section of the device, and

Fig. 5 is a central vertical longitudinal section through one of the glass cover members.

30 In the drawings, the preferred form of embodiment of the invention is shown as comprising a metallic body portion 10 having suitable handles 11 and provided, if desired, with ornamental panels 12. At the sides and 35 ends the metal of the body is preferably turned outwardly and downwardly at its upper edge as shown best in Fig. 2 at 15 and 16 to provide a wide seat at 15 for appearance and more especially for a purpose 40 to be indicated.

A short distance from the upper edge of the body 10 it is preferred to weld or otherwise secure a metallic channel strip of substantially triangular cross section 20, extending 45 outwardly beyond the portion 16, to form a shoulder or ledge 21 serving as a seat for the vault lid as subsequently herein described. And at suitable locations within the body 10, wooden nailing strips 25 will be placed and 50 held fixed by means of suitable metal clips

or brackets 26 preferably spot welded to the metal of the body.

Near the upper edge of the body 10 is welded or otherwise secured, preferably in air-tight relation to the metal of the body, a strip of metal 30 which is bent longitudinally to provide a vertical portion 31 for securing to body 10, and an inwardly projecting portion turned up and back upon itself to provide an outwardly projecting flange 32 spaced from the body wall. This flange 32 serves as means to which the casket cover may be secured as by a plurality of clamps 33.

The casket cover comprises a frame member 40 having a downwardly and outwardly extending flange portion 41 adapted to rest upon the above mentioned flange 32 and be clamped thereon, a suitable gasket 42 being used to seal the junction. The frame member 40 is provided with a central opening for the reception of a plate of glass 43 which may be held in place by an inner frame element 44 screwed or otherwise secured to member 40, a suitable seat 45 being provided for the glass.

The frame member 40 likewise has hinged to it, as at 50, a casket lid 51, preferably arched over the glass 43 and resting upon suitable horizontal portions of the member 40. It is preferred to make the lid 51 in two portions as indicated in Fig. 1 and to provide in the lower recessed side wooden nailing strips 52 also held by suitable welded on clips or straps 53. The strips 52 and 25 are of course for securing proper fabric lines (not shown).

The vault lid 60 consists of sheet metal formed to arch over in any suitable shape the casket lid 51 and extend outwardly to the edge of shoulder 21. The outer edge of the lid 60 being preferably turned down and then inwardly to form a suitable rim 61 adapted to rest upon the shoulder 21, outside of body portion 15.

Channel members one of which is shown at 62 are secured by welding or otherwise to the underside of the vault lid 60 with their backs or closed sides against the latter. Locking or latching means, such as bolts 63, are mounted within the channel members, the bolts 63

engaging channel bars 64 secured to the inner surface of the body 10. Springs 65 tend to project the bolts outwardly for locking purposes, and the springs are held in compression, until it is desired to lock the wall, by means of cotter pins, not shown, residing in apertures 66 and behind the transverse plate 67 when the bolts are in their retracted position and before the lid has been locked to them. There will, of course, be a plurality of such latches and sealing will be had by the use of a suitable gasket 68 pressed between the lid and the upper edge of the body.

Now having described the invention and the preferred forms of embodiment thereof, it is to be understood that the said invention is to be limited, not to the specific details herein set forth, but only by the scope of the claim which follows:

20 I claim:—

A combined casket and vault comprising a body portion having vertical side walls, a flanged member inside of the body portion near the top thereof and secured to the 25 side walls to provide an inner peripheral shoulder, an open frame fixedly secured to said inner peripheral shoulder, a transparent plate in the opening of said frame, a cover hingedly secured to said 30 frame and adapted to cover the transparent plate, a flanged member outside of the body portion near the top thereof and secured to the side walls to provide an outer peripheral shoulder above the inner peripheral shoulder, 35 a vault lid resting upon the outer shoulder to seal the body portion, and spring projected bolts carried by the lid on its under surface inside the body and adapted to engage a portion of the side walls to lock the lid to the 40 body.
